INVENTOR
Harry W. Broady

BY
Joseph J. O'Brien
ATTORNEY

UNITED STATES PATENT OFFICE.

HARRY W. BROADY, OF BAYSIDE, NEW YORK, ASSIGNOR TO AMERICAN BALSA COMPANY, INC., A CORPORATION OF NEW YORK.

DAVIT AND CRANE.

1,388,830.

Specification of Letters Patent. Patented Aug. 23, 1921.

Application filed August 11, 1919. Serial No. 316,775.

To all whom it may concern:

Be it known that I, HARRY W. BROADY, a citizen of the United States, and a resident of Bayside, borough of Queens, county of 5 Queens, and State of New York, have invented certain new and useful Improvements in Davits and Cranes, of which the following is a specification.

This invention relates to improvements in 10 davits.

Under certain conditions it is desirable that the arms or booms of davits and cranes may without disassembly and separation of parts be lowered or swung down close to 15 the deck of the vessel when not in use, and on battleships and other war vessels, it is required by the regulations that all arms or booms of davits or cranes shall be capable of being turned or swung down so that its 20 highest point will not extend more than six feet above the deck.

In mechanically operated davits, and particularly screw-actuated davits of the quadrant type, the extreme inboard position is 25 substantially perpendicular and the boom or davit arm extends very much above the limit allowed. It has, therefore, been a problem to produce a davit of such mechanically operated or quadrant type, the boom 30 of which could without disassembly be turned or swung down below the required limit and which at all times might be readily and quickly moved or hoisted into operative position.

35 The primary object of my invention is, therefore, to produce a davit in which the arm or boom may, without disassembly or separation of the parts, be swung down beyond the extreme inboard position to which 40 it is normally moved by the davit operating mechanism, and particularly the production of such a davit in which the arm is adapted to swing vertically about a pivotal support located between its ends and which support 45 is caused to travel horizontally on a suitable frame to swing the davit.

Another object of my invention is to produce such a davit in which the arm or boom is not only moved by its operating mechanism but which can be released therefrom and moved in relation thereto.

50 Another object of my invention is the provision in combination with such a davit of means whereby the boom or arm of the davit may be quickly and readily swung

from its inoperative, turned-down position to its normally operative position.

Other objects of my invention will be in part obvious from the annexed drawings and in part indicated in connection therewith by 60 the following analysis of this invention.

This invention accordingly also consists in the features of construction, combinations of parts, and in the unique relationship of the members and in the relative proportioning and disposition thereof, all as more completely outlined in the following specification and in said drawings.

To enable others skilled in the art so fully to comprehend the underlying features of my 70 invention that they may embody the same by numerous modifications in structure and relationship of parts contemplated by this invention, drawings depicting a preferred form have been annexed as a part of this 75 disclosure, and in such drawings like characters of reference denote corresponding parts throughout all the views, of which:

Figure 1 is a side elevation of a davit embodying my invention, showing in full lines 80 the davit arm in its normally operative inboard position and showing in dotted lines the outboard position of such arm;

Fig. 2 is a similar elevation of the davit 85 operating mechanism into a position in which the arm will be substantially horizontal;

Fig. 3 is an inboard end view of the davit shown in Figs. 1 and 2; and 90

Fig. 4 is a section on the line 4—4 of Fig. 1.

Referring now to these drawings, 1 indicates a davit arm which, as shown, is of the quadrant type having a lower end quadrant-shaped in conformation and provided with a toothed segment 2 which rolls upon a rectilinear toothed rack 3 preferably cast integrally with a frame 4. The arm 1 also swings in a vertical plane about a pivot 5 located 100 between the ends thereof and the pivot 5 is guided at the top of said frame 4 and caused to move in a rectilinear and substantially horizontal path for the purpose of swinging the davit outboard and inboard from one 105 normal extreme position to the other. All this is old and forms no part of my invention.

As illustrated, the davit arm is so pivoted to swing in a vertical plane on a movable 110

block 6 which slides on a rod 7 mounted at the top of said frame and said block 6 also has a threaded connection with a screw 8 rotatably mounted in said frame below and 5 parallel to said rod. The screw is rotated by a crank 9 co-operating with gears 10, 11, 12 and 13 respectively.

In accordance with the preferred form of my invention illustrated, the davit arm is 10 releasably connected to the traveling pivot 5 and said arm is adapted to be moved relatively to said pivot without complete disconnection therefrom in order to permit further lowering of the davit toward the deck of 15 the vessel. As illustrated, the pivot pin 5 is arranged to bear at one end in an extension 14 of the block 6 and is, as shown, provided at its opposite end with a roller 15 and in the embodiment shown, said pivot 20 extends through an arc-shaped slot 15 formed in the davit arm and extending from the normal pivotal point of the davit rearwardly toward the lower end or heel thereof. Said pivot pin 5 is so releasably connected 25 at the upper end of said slot with the davit arm preferably by means of a plunger or reciprocating block 16 movable by means of a screw spindle 18 in suitable ways in a housing 17 preferably formed integral with 30 the davit arm. As shown, the pivot pin is provided with a transverse slot or opening 19 and the plunger 16 is moved downwardly therethrough and its lower end seats in a depression 20 in the opposite side of the 35 slot 15 so as to procure a firm connection between said pivot pin 5 and the davit arm 1.

When the davit arm 1 is so connected with the pivot pin 5 and block 6, it will be apparent that the rotation of the operating screw by means of the crank handle 9 will cause the davit arm 1 to be swung in a vertical plane from the inboard position shown in full lines in Fig. 1 to the outboard position shown in dotted lines in said figure.

It will also be apparent that when the plunger 16 is withdrawn from the opening in said pivot 5, the davit arm may because of the mounting of said pivot in the slot 15 50 be moved in relation to said pivot from one end of the slot to the other, and that during such swinging the first tooth 23 of the segment will act as a pivot, and such tooth is preferably rounded for this purpose and fits 55 in a suitable depression 23a. The arm may be thus folded down into a position in which the outer end of the arm will be relatively close to the deck of the vessel, and it will also be seen that the parts are not separated 60 but are retained in position ready for quick readjustment into operative position.

In order to permit ready readjustment after a folding of the davit as hereinabove described, I preferably attach to the outer end 65 of the davit a block and falls and connect

the opposite end of such block and falls to the outboard end of the frame 4 preferably by a hook 21 secured in an eye 22 formed in said frame. By such an arrangement, it will be possible to swing the davit about 70 said first tooth 23 and the davit may be swung into its normal inboard position as shown in Fig. 1, whereupon the plunger 16 may be operated by its screw 18 to again connect the parts together. 75

In a construction of this type, the davit arm may be swung from its inboard, operative position to its folded down position with great rapidity and may furthermore be raised from such folded-down position to 80 its operative position also with much greater rapidity than would be possible if the parts were separated or disassembled.

Without further analysis, the foregoing will so fully reveal the gist of this invention that others can by applying current knowledge readily adapt it for various applications without omitting certain features that, from the standpoint of the prior art, might fairly constitute essential characteristics of the generic or specific aspects of the invention, and therefore such adaptations should and are intended to be comprehended within the meaning and range of equivalency of the following claims. 90

Having described my invention, I claim:

1. In a crane or davit, the combination with a suitably supported and pivoted davit arm and operating mechanism engaging said arm intermediate its ends for swinging 100 the same to its normal extreme positions respectively, of means for connecting said arm and said operating mechanism to permit relative movement therebetween to permit swinging of the arm beyond one of such 105 normal extreme positions.

2. In a crane or davit, the combination with an arm supported to swing vertically in a suitable frame and operating mechanism supported in said frame and engaging 110 said arm between its ends for swinging the same to its extreme operative positions respectively, and a releasable connection between said arm and said operating mechanism to permit relative movement therebetween to swing the arm beyond one of its 115 normal extreme positions.

3. In a crane or davit, the combination with an arm supported in a suitable frame to swing in a vertical plane about a point 120 between its ends and having a slot extending from its pivotal point toward its foot, a pivot pin about which said arm is adapted to swing mounted in said slot; operating mechanism engaging said pivot for normally swinging the arm to extreme operative positions respectively, and means for releasably securing said pivot in said slot. 125

4. In a crane or davit, the combination with an arm supported in a suitable frame 130

to swing in a vertical plane about a point between its ends and having a slot extending from its pivotal point toward its foot, a pivot pin about which said arm is adapted to swing mounted in said slot; operating mechanism engaging said pivot for normally swinging the arm to extreme operative positions respectively, a plunger housing formed contiguous to one end of said slot and a screw actuated plunger mounted

in said housing for connecting said pivot to the said arm.

In witness whereof, I have signed my name to the foregoing specification in the presence of two subscribing witnesses.

HARRY W. BROADY.
